LAPPING DEVICE, APPARATUS, AND
METHOD

Herbert S. Indge, Westboro, and Albert G. Bel-
den, Worcester, Mass., assignors to Norton
Company, Worcester, Mass., a corporation of
Massachusetts

Application February 5, 1938, Serial No. 188,898

1 Claim. (Cl. 51—184.1)

The invention relates to lapping devices, apparatus and methods, and with regard to its more specific features to lapping devices, apparatus and methods for lapping the bores of work pieces.

5 One object of the invention is to provide a lapping device for lapping the bore of an article to fine precision limits. Another object of the invention is to provide a lapping device which will readily enter the bore of an article to be lapped 10 and which may be expanded in the bore. Another object of the invention is to provide an improved and facile method of lapping work pieces. Another object of the invention is to provide an efficient and readily controlled lapping apparatus 15 for lapping the bores of work pieces. Other objects will be in part obvious or in part pointed out hereinafter.

The invention accordingly consists in the features of construction, combinations of elements, 20 arrangements of parts, and in the several steps and relation and order of each of said steps to one or more of the others thereof, all as will be illustratively described herein, and the scope of the application of which will be indicated in the 25 following claim.

In the accompanying drawing, showing one of various possible embodiments of the mechanical features of this invention,

Figure 1 is a front elevation of part of a machine upon which the lap of the invention may be mounted and by which it is operated.

Figure 2 is an axial sectional view of the lap and the spindle upon which it is mounted.

Figure 3 is a cross sectional view, taken on the line 3—3 of Figure 2.

35 Referring first to Figure 1, we provide a machine frame 10 of any desired characteristics. Suitably mounted on the machine frame 10 is a motor 11 or any other desired driving mechanism. Mounted preferably on the top of the frame 10 is a work head 12 journailling a spindle 13. The spindle 13 is hollow, as shown in Figures 1 and 2, and is connected by means of a stuffing box 14 to a pipe 15.

45 The motor 11 has an armature shaft 16 on which is mounted a pulley 17 and which shaft 16 extends into a gear pump 18, being direct connected to one of the gears thereof and thereby driving the pump. The pipe 15 is connected to the discharge end of the pump 18 while the inlet of the pump 18 is connected by a pipe 19 to a sump 20. A pipe 21 connects the pipe 15 to a pressure gauge 22 and a relief valve 23, the opening pressure of which is controlled by a handle 24.

On the spindle 13 is a pulley 30 which is connected by a belt to the pulley 17. The spindle 13 is thus rotated whenever the motor 11 is energized.

Referring now to Figure 2, the front end of the spindle 13 is threaded as shown at 35 and a clamping nut 36 is provided to clamp any one of a plurality of laps 37 to the spindle 13. The lap 37 is shown in Figures 2 and 3 and comprises a seamless tube of metal having a flange 38 at one 10 end and a non-plane wall 39 at the other end. The central portion of the lap 37 has cylindrical segmental portions 40 shown in Figure 3 which are spaced from depressions 41, the latter being connected to the segments 40 by portions 42. 15

We further provide a table 45 having mounted thereon a work holder 46 which may comprise an anvil 47 and a movable clamping device 48 actuated by a screw 49 controlled by a hand wheel 50. The table 45 is movable on ways 51 on the frame 20 and may be moved by rotating a screw shaft 52 which fits in a nut 53, the screw shaft being turned by a hand wheel 54.

In operating the apparatus, a suitable work piece W is clamped in the work holder 46 and, 25 a lap 37 having been selected which will fit in the bore of the work piece, the hand wheel 54 is turned to advance the table 45 to carry the work piece to the lap 37, thereby introducing the lap 37 into the bore of the work piece W. Lapping 30 powder or grit is introduced into the work piece or onto the lap either before or as the lap is introduced into the bore. The motor 11 is then energized and the operator controls the lapping action by means of the relief valve 23. The lap 37 35 is capable of expanding since the connecting portions 42 may bend. At the same time, its segments 40, by reason of the pressure against the work piece, are maintained substantially cylindrical. A suitable traverse between work piece 40 and lap may be caused by rotating the hand wheel 54 first in one direction and then in the other.

By means of the lap and apparatus of the invention, lapping or abrading of an article can be achieved on a wide area thereof as distinguished 45 from the slight area of contact between a grinding wheel and a work piece. Furthermore, varying pressures may be applied during the lapping operation and if the lap 37 is made of steel, a given pressure will expand it a given amount. 50 Thus the ultimate diameter of the bore may be readily controlled.

While we have referred to the device as a lapping device, the apparatus as a lapping apparatus and the method as a lapping method, it should 55

- be understood that a substantial amount of material may actually be removed from the work piece thereby, if desired. While the control has been described as hydraulic, so far as certain features of the invention are concerned, we may use pneumatic pressure. The number of segments 40 can be greatly increased if desired or decreased if desired. Furthermore, so far as certain features of the invention are concerned, other shapes of thelapping tool may be adopted. The non-plane portion 39 readily permits expansion at the outer end of the lap and by the use of a traverse, bell mouthing or other distortion of the bore may be avoided.
- It will thus be seen that there has been provided by this invention an article, apparatus and method in which the various objects hereinabove set forth together with many thoroughly practical

advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawing is to be interpreted as illustrative and not in a limiting sense.

We claim:

A lapping tool comprising a tube of metal having an opening at one end, a non-plane wall at the other end, and a central portion comprising a plurality of cylindrical segments joined to depressed portions between the segments.
